US00D572194S

(12) **United States Design Patent**
Lin et al.

(10) **Patent No.:** US D572,194 S
(45) **Date of Patent:** ** Jul. 1, 2008

(54) **CLIPPING COVER**

(75) Inventors: **Kuo Chin Lin**, Tu-Cheng (TW); **Bo Liu**, Tu-Cheng (TW); **Feng Zhu**, Tu-Cheng (TW)

(73) Assignee: **Cheng Uei Precision Industry Co., Ltd.**, Taipei Hsien (TW)

(**) Term: **14 Years**

(21) Appl. No.: **29/270,205**

(22) Filed: **Dec. 19, 2006**

(51) **LOC (8) Cl.** **13-03**

(52) **U.S. Cl.** **D13/133; D13/154**

(58) **Field of Classification Search** D13/133, D13/137.1, 138.1, 139.1, 146, 147, 154, 184, D13/199; 439/43, 95, 92, 93, 172, 252, 247, 439/248, 271, 272, 353, 357-358, 362, 372, 439/378, 527, 529, 538, 569, 680, 558, 606-610, 439/731

See application file for complete search history.
